UNITED STATES PATENT OFFICE.

FRANKLIN C. BREUCKMAN, OF MACKINAC ISLAND, MICHIGAN, ASSIGNOR OF ONE-HALF TO GEORGE THOMAS ARNOLD, OF MACKINAC ISLAND, MICHIGAN.

CARRIAGE-RETURN MECHANISM FOR TYPE-WRITERS.

1,251,746.

Specification of Letters Patent. Patented Jan. 1, 1918.

Application filed July 7, 1917. Serial No. 179,170.

To all whom it may concern:

Be it known that I, FRANKLIN C. BREUCKMAN, a citizen of the United States, residing at Mackinac Island, in the county of Mackinac and State of Michigan, have invented certain new and useful Improvements in Carriage-Return Mechanism for Type-Writers, of which the following is a specification, reference being had to the accompanying drawings.

This invention relates to an improved carriage shifting attachment for typewriters, and has for its object to provide key controlled means for returning the carriage to its initial writing position after writing a line, and at the end of such movement automatically rotating the platen, whereby the lines will be properly spaced.

It is another and more particular object of my invention to provide a device for the above purpose which is particularly designed for attachment to the Underwood standard typewriter, without necessitating alterations of any character whatsoever in the construction of such machine.

It is a further and more particular object of my invention to provide an attachment for the above purpose, including a piston operatively connected to the carriage of the typewriter, and a key-actuated valve for admitting a pressure fluid to the piston cylinder whereby the carriage is shifted to its starting position.

And it is another object of the invention to provide a very simple and reliable device which may be easily attached to the typewriter for automatically operating the platen rotating mechanism at the end of each writing line.

The invention further contemplates the provision of mechanism whereby the above stated objects may be efficiently accomplished, which is of relatively simple construction, strong and durable, and will not add materially to the manufacturing cost of such machines.

With the above and other objects in view, my invention consists in the novel features of construction, combination, and arrangement of parts to be hereinafter more fully described, claimed, and illustrated in the accompanying drawings, in which,

Figure 1 is a front elevation of a typewriter having my improved attachment applied thereto; 55

Fig. 2 is a top plan view;

Fig. 3 is a side elevation;

Fig. 4 is a sectional view taken on the line 4-4 of Fig. 3;

Fig. 5 is a detail sectional view through 60 the valve;

Fig. 6 is a section taken on the line 6-6 of Fig. 4;

Fig. 7 is a section taken on the line 7-7 65 of Fig. 2;

Fig. 8 is a section taken on the line 8-8 of Fig. 2; and

Fig. 9 is a detail perspective view of the slide member removed from the carriage frame. 70

Referring in detail to the drawings, 5 designates the carriage frame of an Underwood typewriter, having the usual paper guide plate 6 and the platen roller 7. As the construction, mounting, and manner of 75 operation of the carriage is well known in the art, and constitutes no part of my present invention, the same will not be further referred to in detail. It will suffice for the purposes of the present explanation, 80 to state that the carriage frame includes the front longitudinal bar 8 which is of angular form in cross-section. Centrally of this bar, the usual outwardly projecting pointer or index member 9 is arranged for movement 85 over the scale bar 10. 11 designates the finger bar, by means of which the platen rotating mechanism is actuated.

At the rear of the typewriter, a pair of supports 31 are arranged in spaced relation, 90 each of said supports consisting of a metal bar bent upon itself to provide an intermediate, annular clamping band 32. Immediately below this intermediate annular portion of the supporting bar, a clamping 95 bolt 33 connects the spaced portions of the bar whereby the band may be tightly clamped around one end of a horizontally arranged cylinder 34. From the clamping bolt 33, the spaced portions of the bar 31 extend downwardly in divergent relation and have their terminal portions angularly bent inwardly toward each other, as at 35, and secured to the ends of a metal bed plate 36 100

by the screws 37 which also secure the felt or rubber disks 38 upon the under side of said plate.

A guard rail 39 is secured upon the upper 5 ends of spaced supports 40, said guard rail being of hollow, rectangular form in cross-section and having a continuous longitudinally extending slot 41' in its top wall. One end of this guard rail is formed with a longitudinal extension which is seated within the 10 clamping band 32 which supports the right hand end of the cylinder 34. This end of the cylinder is provided with a detachable threaded cap 41 having a suitable stuffing box through which the piston rod 42 extends. A piston 43 of any approved construction is fixed to one end of this rod for reciprocation within the cylinder 34. The other end of the piston rod 42 is formed 15 with a reduced portion around one side of which the lower end of a vertically disposed arm 44 extends. The plate 45 is engaged against the other side of this reduced portion of the piston rod and riveted or otherwise 20 securely fixed to the arm 44. The lower end of the arm 44 and plate 45 extends downwardly through the slot 40' in the guard rail 39, and upon the same a pair of anti-friction rollers 46 are rotatably mounted 25 to travel in the hollow rail. The upper end of the arm 44 is forwardly curved, as at 47, and provided with terminal means indicated at 48, for attachment to the beaded upper edge of the plate 6 which directs the 30 paper to the platen of the typewriter.

The opposite or left hand end of the cylinder 34 is connected by a short pipe 49 to one end of the valve casing 50. In this casing, a rotary valve member 51 is arranged, having 35 a longitudinally extending channel 52 in its periphery, one end of which is adapted to register with the pipe connection 49 and the other end with an exhaust port 53 formed in the wall of the valve casing. This valve member is further provided in its periphery and in spaced relation to the channel or duct 52 with a second channel having a relatively short, longitudinally extending end portion 54 and a long, obliquely 40 inclined portion 55. The end portion 54 is adapted to register with the pipe connection 49 when the valve member is rotated, while the end of the oblique portion 55 of the channel is adapted to register with one end of a supply pipe 56 connected to the valve casing and to a suitable tank or reservoir which contains air under pressure. Air may be periodically supplied to the tank or reservoir by either a foot or power actuated pump, the latter preferably being used to supply the 45 cylinders 34 of a large number of typewriters.

One end of the valve 51 is formed with a cylindrical stem 57 rotatably engaged in a 50 detachable head 58 threaded upon one end

of the valve casing 50. An arm 59 is fixed to the extremity of this stem by means of a suitable screw indicated at 60.

In order to securely brace the supports for the cylinder 34 and the guard rail 39, 55 the end supports are secured to the foot pieces fixed to the corners of the typewriter frame by means of the metal clamping bands 61 which extend around the foot pieces and around the respective supporting 75 bars adjacent one of their ends. The terminals of the clamping bands are connected by means of the clamping screws 62.

To one end of the typewriter frame and to an inwardly projecting lug on the lower edge 80 thereof, one arm of an angular metal plate 63 is secured by means of the screw indicated at 64. The other arm of this plate projects upwardly alongside of the frame, and upon this arm a lever 65 is pivotally mounted intermediate of its ends, as at 66. The rear end of this lever is angularly bent, as at 67, and operatively connected by means of the link 68 to the end of the valve operating arm 59. The other or forward end of 90 this lever projects upwardly and is equipped with a suitable finger cap piece 69 which is disposed in line with and adjacent to the left hand shift key.

In the operation of the carriage shifting 95 attachment as above described, it will be understood that normally, or while the carriage is moving from right to left, the passage or duct 52 of the rotary valve member 51 connects the left hand end of the cylinder 100 34 with the exhaust port 53 so that the piston 43 will have unretarded movement in said cylinder in one direction during the step by step movement of the carriage. When a line has been written, the operator de- 105 presses the forward end of the lever 65, thereby raising the rear end thereof and through the medium of the link 68, rotating the valve 51 in a direction to connect the left hand end of the cylinder 34 with the compressed air supply pipe 56 through the medium of the passage or duct 54, 55 in the periphery of the valve. Highly compressed air is thus admitted to the left hand end of the cylinder 34 which acts against the piston 110 43 so that the carriage will be shifted to the full limit of its movement toward the left into position for the writing of a new line. Preferably, though not necessarily, I provide a coil spring indicated at 70, attached 115 to the rear end of the lever 65 and at a suitable point on the machine frame to positively return the rotary valve 51 to its normal position when the lever is released and overcoming any tendency of the air pressure 120 against said valve to hold the same stationary, as might occur if the gravity movement of the rear end of the lever and the link connection 68 were alone relied upon for the performance of this function. It will 125 130

thus be observed that immediately upon a continuance of the step by step movement of the carriage in writing, communication will be opened between the cylinder 34 and the atmosphere so that the movement of the piston 43 will not be retarded.

In addition to the carriage shifting means which I have above described, I have also devised a very simple and effective device 10 for actuating the rotating mechanism for the carriage platen, whereby the written lines are properly spaced. This device I shall now proceed to describe in detail.

Upon the rear side of the carriage frame 15 bar 8 at its center, one end of an arm 12 is secured by means of the screw indicated at 13. This arm extends obliquely upwardly and forwardly and its other end which is disposed immediately above the forwardly 20 projecting enlargement on said bar is of inverted U-shaped form, as indicated at 14. This end of the bar constitutes a bearing to receive the trunnions of a roller 15. A strip of woven tape or webbing 16 extends 25 over this roller, and one end of said tape is attached to the under side of the finger bar 11 in advance of the carriage frame bar 8 by means of the screw 17.

Upon the bar 8 on the right hand side of 30 the bar 12 and in spaced relation thereto, a plate 18 is arranged, one edge of said plate being bent downwardly and inwardly, as at 19. This plate at its other edge is securely fixed to the frame bar 8 by means 35 of spaced screws 20 which also secure to the frame bar a second relatively narrow metal plate 21 disposed between the edge of the plate 18 and the frame. This plate 21 has its outer edge, which projects beyond the 40 edge of the bar 8, downwardly offset, as at 22, and disposed in the same plane with the inwardly turned edge portion 19 of the plate 18. The opposed edges 19 and 22 of the metal plates are spaced from each other 45 and also from the under side of the plate 18, thereby forming a guideway 23 to receive the flange 25 formed upon one end of a lug 24 which extends downwardly below the plate 18. Upon the right hand end of 50 the plate 18, a roller 26 is mounted in spaced bearings 27 fixed to the end edge of the plate, and over this roller the tape 16 is engaged. The end of the tape is provided with a suitable eye for engagement with a 55 headed stud 28 fixed in the flange 25 on the lug 24.

29 designates the adjustable carriage stop with which the typewriter is equipped, said stop limiting the movement of the carriage 60 and determining the length of the written lines. To the rear portion of this adjustable stop, an upwardly projecting finger or lug 30 is suitably fixed.

From the above description, the manner 65 of operation of this portion of my inven-

tion will be readily understood. When the carriage is returned to its initial position by means of the above described key controlled, air actuated means, just prior to the end of such movement, the lug 24 strikes 70 the upwardly projecting finger 30 on the adjustable carriage stop and shifts this lug 24 in the guideway 23 formed by the plates 18 and 21. The end of the tape 16 being attached to the flange 25 on said lug, it is 75 apparent that the tape will be pulled around the roller 26, and as the other end of the tape is connected to the spring-held, manually operable lever 11, this lever will be pulled over toward the right and the platen 80 rotating mechanism will be actuated to rotate the platen to the extent for which the mechanism has been adjusted. As the use of my invention necessitates no changes 85 whatever in the construction of the platen rotating mechanism as now used in machines of the type referred to, it is not deemed necessary to illustrate or describe such mechanism in detail. Of course, as the writing proceeds and the carriage moves 90 toward the left, the lug 24 moves away from the upstanding finger 30 and the lever 11 is returned to its normal position by means of the lever spring, thereby also returning the lug 24 to its original position 95 in the right hand end of the guideway 23.

From the foregoing description, taken in connection with the accompanying drawings, the construction, manner of operation, and several advantages of my improved 100 typewriter attachment will be clearly and fully understood. It will be manifest that the invention can be easily and quickly applied to the typewriter without in any way changing the construction of the parts of 105 the machine or the machine frame, or impairing the easy and free operative movement of the carriage or the platen. By resorting to simple mechanical changes in the form, mounting, and arrangement of the 110 several elements of the invention, the latter may also be adapted to other makes of typewriting machines than that herein particularly referred to. It is also to be observed that the use of my improved attachment in 115 nowise interferes with the free access to the type bars or other parts of the machine in cleaning the same. The carriage shifting and rotating mechanism is instantaneous 120 in its action so that there will be practically no interruption in the manipulation of the type keys as now occurs owing to the fact that the operator must lift the hand to manually return the carriage to its initial position and rotate the platen for the writing 125 of another line.

I have herein specifically described what, at the present time, I believe to be the preferred embodiment of the invention, and I, therefore, reserve the privilege of making 130

all such mechanical alterations as I may hereafter find advisable and as may be fairly considered as falling within the spirit and scope of the appended claims.

5 Having thus fully described my invention, what I desire to claim and secure by Letters Patent is:

1. The combination with a typewriter carriage, of a cylinder, a guideway extending longitudinally from one end of the cylinder, a fluid actuated piston in the cylinder having a rod, means mounted to travel in said guideway and rigidly connecting the rod to the typewriter carriage, and key actuated means for controlling the admission of a pressure fluid to said cylinder.
- 10 2. The combination with a typewriter carriage, of a cylinder, a guideway extending longitudinally from one end of the cylinder, a fluid actuated piston in the cylinder having a rod, means mounted to travel in said guideway and rigidly connecting the rod to the typewriter carriage, and key actuated means for controlling the admission of a pressure fluid to said cylinder.

15 2. The combination with a typewriter carriage, of a cylinder, a guideway extending longitudinally from one end of the cylinder, a fluid actuated piston in the cylinder having a rod, means mounted to travel in said guideway and rigidly connecting the rod to the typewriter carriage, and key actuated means for controlling the admission of a pressure fluid to said cylinder.

riage, of a cylinder mounted at the rear thereof, a fluid actuated piston in the cylinder having a rod, a hollow rail, an arm 20 fixed to the end of the piston rod and operatively connected to the carriage, anti-friction means on the lower end of said arm to travel longitudinally in the hollow rail, a rotary valve adapted in one position 25 to connect the cylinder with a source of fluid under pressure, and means for operating said valve to admit the pressure fluid to the cylinder, whereby the carriage is returned to its initial writing position.

30

In testimony whereof I hereunto affix my signature in the presence of two witnesses.

FRANKLIN C. BREUCKMAN.
